CLOCKCASE

Meyer Schwartz, Chicago, Ill., assignor to La Salle Novelty Company, a partnership composed of Meyer Schwartz and Deris Ellman, Chicago, Ill.

Application September 20, 1950, Serial No. 12,269

Term of patent 7 years

(Cl. D42—7)

To all whom it may concern:

Be it known that I, Meyer Schwartz, a citizen of the United States and resident of Chicago, in the county of Cook and State of Illinois, have invented a new, original, and ornamental Design for a Clockcase, of which the following is a specification, reference being had to the accompanying drawings forming a part thereof.

Fig. 1 is a front elevational view of a clockcase, embodying my new design.

Fig. 2 is a view of one side thereof.

Fig. 3 is a view of the other side thereof.

Fig. 4 is a top plan view thereof.

Fig. 5 is a bottom view thereof.

Fig. 6 is a back view thereof.

The dominant portions of the design are shown in full lines.

I claim:

The ornamental design for a clockcase, substantially as shown and described.

MEYER SCHWARTZ.
